CLAIM

The ornamental design for an UVC LED wash sterilizing bag, as shown and described.

DESCRIPTION

FIG. 1 is a perspective view of an UVC LED wash sterilizing bag, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The short, even length broken lines are of stitching that form part of the claimed design. The wide, even length broken lines are for the purpose of illustrating portions of the UVC LED sterilizing bag that form no part of the claimed design.
